(57) **CLAIM**

The ornamental design for a laundry detergent holder, as shown and described.

DESCRIPTION

FIG. 1 is a top perspective view of a laundry detergent holder of the present invention.

FIG. 2 is a bottom perspective view of FIG. 1.

FIG. 3 is a front view of FIG. 1.

FIG. 4 is a rear view of FIG. 1.

FIG. 5 is a left side view of FIG. 1.

FIG. 6 is a right side view of FIG. 1.

FIG. 7 is a top view of FIG. 1.

FIG. 8 is a bottom view of FIG. 1; and,

FIG. 9 is an exploded view of FIG. 1.

The broken lines illustrate the portion of the laundry detergent holder and form no part of the claimed design.
